ROTARY SELECTOR SWITCH

Herbert R. Warnke, East Orange, N. J., assignor
to United States Instrument Corporation, East
Orange, N. J., a corporation of New Jersey

Application May 24, 1944, Serial No. 537,088

8 Claims. (Cl. 200—11)

1

This invention relates to electrical switches and more particularly to a multi-position selector switch for use in inter-communication systems, signal systems and the like where a compact selector switch enabling connection with one of a multiplicity of circuits is desired.

It is the general object of the present invention to provide a rotary selector switch of a compact design having low contact resistance, large current capacity, rugged construction, and long life.

More particularly, it is an object of the invention to provide a rotary selector switch having one or more banks or decks of terminals, the terminals of each bank being arranged in circular spaced relationship, and having a common central terminal and a rotating contact arm with means thereon for maintaining constant sliding engagement with the common terminal and other means thereon for successively engaging the individual terminals as the contact arm is rotated. A particular feature of the invention lies in the provision of a solid silver contact member, carried on the afore-mentioned contact arm, which bridges the space between the annular common terminal and the individual terminals, serving as a direct and short path of high current carrying capacity.

Another feature of the invention lies in the provision of an auxiliary contact arm, electrically connected to the first contact arm and also adapted to engage the individual terminals successively, providing a second current path between the common terminals and the individual terminals. It is also a feature of the invention that the several sliding contact members are of solid coin silver, providing high current-carrying capacity, low contact resistance and long life. The contact arms are of a metal possessing good resilience and satisfactory conductance, they are adjusted in such a way as to maintain a light but constant spring pressure forcing the silver contact members into firm engagement with the contact portions of the respective terminals, the adjustment being such that the resilience of the contact arms will serve to compensate for any wear of the contact members or terminals.

Other and further features and objects of the invention will be apparent from the description which follows, read in connection with the accompanying drawings, in which:

Figure 1 is a rear elevation of a switch constructed in accordance with the present invention;

Figure 2 is a side elevation of the switch shown in Figure 1;

2

Figure 3 is a sectional view on line 3—3 of Figure 1;

Figure 4 is a sectional view on line 4—4 of Figure 1;

5 Figure 5 is a view similar to Figure 1 but with all of the individual terminals except one omitted for clarity, and with the auxiliary contact arm broken away to expose the main contact arm;

10 Figures 6, 7, 8, and 9 are detail views illustrating, in plan, the auxiliary contact arm, the main contact arm, the common terminal, and the contact support disk, respectively;

15 Figure 10 is a rear elevation of the base plate illustrating the switch indexing means seen in side view in Figure 2; and

Figure 11 is a sectional view on line 11—11 of Figure 10.

20 In order to facilitate an understanding of the invention, reference is made to the embodiment thereof shown in the accompanying drawings, and detailed descriptive language is employed. It will nevertheless be understood that no limitation of the invention is thereby intended and 25 that various changes and alterations are contemplated such as would ordinarily occur to one skilled in the art to which the invention relates.

Referring now to Figures 1, 2, and 3, it will be seen that the switch comprises generally a base plate 10 in which a shaft 11 is rotatably mounted by means of a bushing 12, a handle 13 being provided for turning the shaft 11, and one or more (in the present case, two) generally annular terminal supports 14 of suitable rigid insulating material, such as Bakelite, each of which is provided with a plurality of terminals 15, which may be of bronze coated with silver. The terminals 15 may be secured to the supports 14 by any suitable means, as for example by hollow rivets 16. The outer ends of the terminals 15 are inclined at an obtuse angle to the plane of the support and are apertured to facilitate the securing of conductors thereto. The inner ends of the terminals 15 lie flat against the adjacent surface 45 of the support 14 and serve as contact portions of the respective terminals, for engagement with the contact means to be described. The supports 14 are maintained in spaced relationship by means of the bolts 17 and spacers 18.

50 That portion of the shaft 11 which lies inwardly of the base plate 10 is flattened as at 19 and carries the indexing disk 20 and the rotating contact supports 21, which latter are comprised of disks of insulating material, such as Bakelite, of substantially the diameter of the central openings in

the terminal supports 14. As best seen in Figure 4 a common terminal 22, preferably of bronze, annular in form, is secured to the terminal support 14 surrounding and partially overlying the central opening of the latter and the contact support disk 21 which rotates within said central opening. The common terminal 22 is provided with an extension 22' (Figures 1 and 3) for connection to a conductor.

The main contact arm 23, which is shown in detail in Figure 7, is mounted on the contact support 21, and spaced therefrom, by rivets 24, and carries two sliding contact members 25 and 26, secured thereto in any suitable manner. In the illustrated embodiment the contact members 25 and 26 are solid coin silver and are provided on their upper side with integral bosses 25', 26', extending through apertures in the material of the contact arm 23, and upset or peened to secure the contact members to the arm. It will be noted that the downwardly projecting portions of the contact members 25 and 26 are inclined to the major axis of the contact arm whereby they wipe the contact surfaces of the respective terminals over larger areas, reducing wear and at the same time providing a self-cleaning feature. The contact member 26 has two such downwardly projecting portions, one at each end, for engagement with the common terminal 22 and individual terminals 15, respectively, while the contact member 25 also engages the common terminal 22, but not the individual terminals.

A second or auxiliary contact arm 27, shown in detail in Figure 6 overlies and is secured to the contact arm 23, being secured by the same rivets 24 which fasten the latter to the support member 21, and is thus in electrical contact with contact arm 23. The auxiliary contact arm 27 carries a contact member 28, which is secured to a down-turned flange 29 of the contact arm by means of integral bosses 30 as described above. The contact member 28, like the others, is inclined to the axis of the contact arm, and is adapted to engage only the individual terminals 15, providing an alternate current path between contact arm 23 and the terminals 15. Thus in all there are two silver contact members engaging the common terminal 22, and two engaging the individual terminals, the latter two engaging the same individual terminal at any given time. Furthermore, the bridge-like contact member 26 provides a short and direct path of high current-carrying capacity between the common terminal and the individual terminals.

The contact arms 23 and 21 are of metal possessing good resilience and satisfactory current-carrying capacity, for example beryllium copper, and are adjusted to exert a slight constant pressure upon the contact members forcing them into firm engagement with the respective terminals. Due to the length and flexibility of the contact arms, this spring pressure, though slight, will take up any wear to which the contact surfaces may be subject during the lifetime of the switch.

The indexing mechanism, best seen in Figure 10, comprises the toothed disk 29, secured on the flattened portion 19 of the shaft 11, levers 31 pivoted as at 32 to the plate 18, cam follower rollers 33 carried by the levers 31, and tension springs 34 secured between the free ends of the levers 31 and studs 35 carried by the base plate 10. The valleys formed in the periphery of the disk 20 correspond in number and spacing to the terminals 15 of the respective terminal supports. It will be readily understood that by virtue of the mecha-

nism just described, when the handle 13 is grasped and the shaft turned to a selected position, the disk 20 will be rotated, each successive tooth passing under the rollers 33 forcing the levers 31 outwardly against the pressure of the springs 34, and each successive valley passing under the rollers 33 permitting the levers to swing inwardly again. Thus when the selected position is reached, the rollers 33 are firmly seated in the corresponding valley of the disk 20 and the switch is firmly maintained in the selected position until positively actuated.

In the illustrated embodiment, the switch of the present invention is especially adapted for an intercommunication or signalling system in which a master station is to be selectively connected with any one of sixteen subordinate stations by means of a two-wire circuit. However, switches constructed in accordance with the invention may be adapted to a wide variety of useful purposes and the number of decks or banks of individual terminals may be multiplied to any desired number in order to meet the particular purpose at hand.

From the foregoing description it will be apparent that the objects enumerated above are achieved by the invention, and a compact, rugged, and efficient all-purpose rotary selector switch is provided.

Having thus described the invention, what is claimed as new and desired to be secured by Letters Patent is:

1. In a multi-position switch, a base plate, a plurality of generally annular terminal plates supported from said base plate in spaced, aligned relation, a plurality of terminal members supported in circular, spaced relation on each said terminal plate, each said terminal member having a contact portion, a shaft rotatably mounted in said base plate and extending through the central openings of said terminal plates, a plurality of contact supports carried by said shaft, one said contact support being substantially in the plane of each said terminal plate, a contact arm mounted on each said contact support, a common terminal mounted on each said terminal plate and having an annular contact portion surrounding the central opening therein, contact means carried on each said contact arm for slidably engaging the contact portion of the adjacent common terminal, and contact means carried on each said contact arm for successively engaging the contact portions of the adjacent terminal members as said shaft is rotated.

2. In a multi-position switch, a base plate, a plurality of generally annular terminal plates supported from said base plate in spaced, aligned relation, a plurality of terminal members supported in circular, spaced relation on each said terminal plate, each said terminal member having a contact portion, a shaft rotatably mounted in said base plate and extending through the central openings of said terminal plates, a plurality of contact supports carried by said shaft, one said contact support being substantially in the plane of each said terminal plate, a contact arm mounted on each said contact support, a common terminal mounted on each said terminal plate and having an annular contact portion surrounding the central opening therein, contact means carried on each said contact arm for slidably engaging the contact portion of the adjacent common terminal, and contact means carried on each said contact arm for successively engaging the contact portions of the adjacent terminal members as said shaft is rotated.

terminal members as said shaft is rotated, said last contact means being an integral bridge-like member having a portion adapted to slidably engage the contact portion of the adjacent common terminal in all positions of the contact arm, thereby providing a direct and short current path between said common terminal and said terminal members.

3. In a multi-position switch, a base plate, a plurality of generally annular terminal plates supported from said base plate in spaced, aligned relation, a plurality of terminal members supported in circular, spaced relation on each said terminal plate, each said terminal member having a contact portion, a shaft rotatably mounted in said base plate and extending through the central openings of said terminal plates, a plurality of contact supports carried by said shaft, one said contact support being substantially in the plane of each said terminal plate, a contact arm mounted on each said contact support, a common terminal mounted on each said terminal plate and having an annular contact portion surrounding the central opening therein, contact means carried on each said contact arm for slidably engaging the contact portion of the adjacent common terminal, and contact means carried on each said contact arm for successively engaging the contact portions of the adjacent terminal members as said shaft is rotated, each said contact means being of solid coin silver.

4. In a multi-position switch, a base plate, a plurality of generally annular terminal plates supported from said base plate in spaced, aligned relation, a plurality of terminal members supported in circular, spaced relation on each said terminal plate, each said terminal member having a contact portion, a shaft rotatably mounted in said base plate and extending through the central openings of said terminal plates, a plurality of contact supports carried by said shaft, one said contact support being substantially in the plane of each said terminal plate, a contact arm

mounted on each said contact support, a common terminal mounted on each said terminal plate and having an annular contact portion surrounding the central opening therein, contact means carried on each said contact arm for slidably engaging the contact portion of the adjacent common terminal, contact means carried on each said contact arm for successively engaging the contact portions of the adjacent terminal members as said shaft is rotated, and means for indexing said shaft at a plurality of positions corresponding to said terminal members.

5. In a rotary switch according to claim 1, an auxiliary contact arm carried on each said contact support and electrically connected to the said contact arm thereon, and contact means on each said auxiliary contact arm for successively engaging said adjacent terminal members, thereby providing a second current path between said contact arm and said terminal members.

6. In a rotary switch according to claim 1, an auxiliary contact arm carried on each said contact support and electrically connected to the said contact arm thereon, and contact means on each said auxiliary contact arm for successively engaging said adjacent terminal members, thereby providing a second current path between said contact arm and said terminal members, said last means being of solid coin silver.

7. A rotary switch according to claim 4, said indexing means comprising a toothed disk mounted on and rotatable with said shaft, a lever pivotally mounted on said base plate adjacent said disk, a cam follower carried by said lever and adapted to engage the toothed periphery of said disk, and resilient means acting on said lever for maintaining said cam follower in engagement with said disk.

8. A switch as defined in claim 1, each said contact arm being of metal possessing good resilience and satisfactory electrical conductance, and each said contact means being of solid coin silver.

HERBERT R. WARNKE.
